UNITED STATES PATENT OFFICE.

SIDNEY C. WILSON, OF ROCHESTER, NEW YORK, ASSIGNOR TO WILSON PROCESS, INCORPORATED, OF NEW YORK, N. Y., A CORPORATION OF NEW YORK.

INSIDE LIP-TURNING MACHINE.

Application filed August 24, 1922. Serial No. 583,993.

To all whom it may concern:

Be it known that I, SIDNEY C. WILSON, a citizen of the United States, and a resident of Rochester, in the county of Monroe and State of New York, have invented an Improvement in Inside Lip-Turning Machines, of which the following description, in connection with the accompanying drawings, is a specification, like letters on the drawings representing like parts.

My present invention relates to shoe manufacturing machines, and more particularly to an inside channel laying machine.

The present invention is particularly designed for use in the manufacture of boots and shoes according to the well known Wilson process, such as is clearly shown and described in my Patents Nos. 1,421,347 and 1,424,745, dated June 27, 1922, and Aug. 1, 1922, respectively. In shoes manufactured according to the well known Wilson process, the grain side of the insole, or that part of the insole that comes in contact with the foot of the wearer, is provided with a marginal channel in which the through and through stitching for the insole, upper, and outsole, is located, the channel flap being in the finished shoe laid down against the insole, thus concealing the line of stitching and rendering the entire inner surface of the insole of the shoe smooth and preventing the objectionable feature of having the line of stitching exposed to cause annoyance to the wearer. During the process of manufacture, and prior to the lasting of the upper to the insole, the channel flap, above referred to, is laid over to expose the channel and this channel, as well as the face of the channel flap, is coated with glue. Heretofore the method of operation has been to lay this channel flap down to conceal the line of stitching by hand, and on small sizes of shoes particularly, this has been an exceedingly difficult operation to perform and one that it is well nigh impossible to perform by hand. The object of my present invention, therefore, is an improved machine for wetting the marginal channel and channel flap and laying such flap down against the channel of the insole to conceal the line of stitching.

In the accompanying drawings illustrating the preferred embodiment of my invention:

Fig. 1 is a plan view, partly in section;

Fig. 2 is a vertical longitudinal section; Fig. 3 is a fragmentary view of the wetting horn, the wetting element being shown in vertical longitudinal section, and

Fig. 4 is a vertical longitudinal section through the sediment pot.

Referring to the drawings, 10 designates a hollow base to the upper end of which is secured a hollow member 11 by bolts 12, this hollow member 11 being provided with radially extending hollow arms 13 and 14 respectively, these arms being located at substantially right angles with respect to each other and the space therebetween being connected by a membrane or plate 15 provided with a ledge 16 on its upper edge, the plate 15 forming a work bench. Securely attached to the top of the member 11, in any suitable manner, is a substantially cone shaped hollow member 17 provided, at its top end, with a plurality of upwardly and outwardly extending arms 18, having formed integral therewith an annular plate 19. Secured to the annular plate 19, and extending above the same, is a conical heating coil 20 to the lower end of which is connected a supply pipe 21 leading to a source of water supply while the upper end is connected by pipe 22 to a pipe 23, a needle valve 24 being inserted between the pipes 22 and 23. Beneath the heating coil 20 is a heating element 25, to the lower end of which is connected a conduit 26 which conduit 26 may lead to a source of fuel, as gas, or may be the enclosing element for wires leading to a source of electricity, depending on whether the heating element 25 is a gas heating element or an electrical heating element.

To the upper outer end of the arm 13 is placed a drip pan 27 and on this drip pan is placed a hollow horn 28, bolts 29 being employed to securely fasten the drip pan 27 and wetting horn 28 to the arm 13. The upper end of the wetting horn 28 is formed as an elongated cup 30, in which fits a wetting element comprised of a body member 31 provided with a longitudinal groove 32 and with a chamber 33, a plurality of perforations 34 extending from the chamber 33 into the longitudinal groove 32. The lower face of the member 31 is provided with a boss 35 drilled and tapped to receive the upper end of a threaded pipe 36 that extends downwardly through the wetting horn 28 and is connected to an elbow 37 in the

hollow arm 13. The other end of this elbow 37 is connected to one end of a pipe 38, the other end of which is connected to an elbow 39 secured to the lower end of the pipe 23. The member 31 is rather a snug fit in the elongated cup shaped member 30 and this member 31 is provided with a plurality of peripheral grooves 40. The upper end of the member 31 is tapered, as shown at 41 in Fig. 1. The member 31 fits into the elongated cup shaped member 30 in the manner indicated in Fig. 3, the lower surface of the member 31 and the lower inner surface of the member 30, defining a chamber adapted to receive the water, or other fluid, that issues from the perforations 34. The used water that passes through the grooves 40 into the chamber above defined, passes downwardly through the interior of the wetting horn 28 and into the drip pan 27 from whence it is led by pipes 42, 43, and 44 into a sediment pot 45 through a passage 46 and nipple 47 into the lower portion of such sediment pot. Referring to Fig. 4, it will be noted that such sediment pot 45 comprises an upper member 48 to the under interior face of which is a depending member 49 in which is located the passage 46, the upper end of this passage 46 being threaded at 50 to receive the lower end of the pipe 44 and the lower end of this passage being threaded to receive the nipple 47. The wall of the member 48 near the upper end thereof is threaded and tapped at 51 for a purpose to be hereinafter described. The lower end of the member 48 is threaded at 52 to receive the internally threaded member 53 formed integrally with the sediment chamber 54, this sediment chamber being provided on its exterior with lugs 55 that are utilized when it is desired to screw or unscrew the sediment chamber from the member 48. Located between the members 48 and 54, and held in place both by such members and by the nipple 47, is a wire screen 56 to the peripheral edges of which, and on each face thereof, are rubber washers or gaskets 57. Located within the base 10 is a pump 58, the plunger 59 of which is connected by connecting rod 60 to a crank 61 secured to a shaft 62 rotatably mounted in a bearing 63 formed integral, and at one side of, the base 10 and in a bearing 64 formed in angular strut 65 secured in any appropriate manner to the base 10. Tight and loose pulleys 66 and 67 respectively, are mounted on the shaft 62. Secured to the hollow member 11 by bolts 68 is a bearing 69 on which is slidably mounted a member 70 carrying belt engaging arms 71. To the upper face of this member 70 is secured a pin 72 which is associated with the fork end of a lever 73, this lever 73 being pivoted intermediate its ends to a member 74 secured to the hollow

member 11 by bolts 75. To the other end of this lever 74 is pivotally attached one end of a link 76, the other end of this link being pivotally attached to a shipping lever 77 which is pivotally mounted intermediate its ends to the lower face of the plate 15, this shipping lever being provided with a handle portion 78 located, as is evident from an inspection of Fig. 1, within convenient reach of the operator. 75

Connected to the drilled and tapped hole 51 in the casing 48 of the sediment pot is a pipe 79 having a choke valve 80 and the other end of this pipe is connected to an elbow 81 to which is connected one end of a pipe 182 that in turn is connected to pipes 83 and 84 respectively, the pipe 84 being connected in the usual manner to the inlet side of the pump 58. On the outlet side of the arm 78 is a pipe 85 connected to any convenient source of drainage. 80

Mounted on the member 17 is a pilot light 86 which is preferably connected in the usual manner in series with an electric heating element 87 that is mounted at the top of a horn 8 secured to the top outer surface of the arm 14 by bolts 89. 85

The operation of my improved device is as follows, assuming that it is desired to lay down the channel flap of a shoe manufactured according to the well known Wilson process: 95

The heating element 25 is started in operation, obtaining its fuel through the supply pipe 26 and at the same time water is fed to the heating coil 20 through the pipe 21, the needle valve 24 being assumed to be at this time closed. Also, the heating element 87 has the current turned on and the fact that such current is passing through the heating element is indicated by the pilot lamp 86 that is in series therewith. When the water in the heating coil 20 is presumed to be hot enough, the needle valve 24 is operated to allow the heated water to flow through the pipes 23, 38, and 36 into the chamber 33 from whence the water issues practically in the form of steam through the perforations 34. The shoe is placed over the elongated member 30 so that the steam arising through the perforations 34 will act on the channel and open the channel flap on the interior of the shoe, softening the leather and also the glue with which the channel and channel flap are coated. From the wetting horn, the shoe is placed on to the heating element on the horn 88 and the channel flap pressed and ironed down into position to close the channel and conceal the line of stitching in the insole. The above sequence of operations is repeated indefinitely. As the work progresses, the excess of water passes down through the V shaped passages 40 and into the hollow arm 28, carrying with it the loose glue, leather, pow- 100

der, etc., and gathers in the drip pan 27. The operator at this stage operates the lever 77 to control the shipping arms 71 and move the belt (not shown) from the loose pulley 67 over onto the tight pulley 66, causing the operation of the pump 58, which pump will, by means of the pipes 84, 83, 82, and 79, draw the accumulated water from the top chamber of the sediment pot 45. As all the water drawn from such sediment pot must first pass upward through the screen 56, it is necessary periodically to clean such sediment pot, which is done by unscrewing the member 54, cleaning out the sediment that has collected therein, and replacing the same.

While I have necessarily described the preferred embodiment of my invention somewhat in detail, it is to be understood that I may vary the details of construction and arrangement of the elements described within wide limits without departing from the spirit of the invention.

Having thus described my invention, what I claim as new is:

1. In a machine of the class described, the combination of a hollow base, a platform secured to the top thereof, a drip pan mounted on said platform, a hollow wetting horn mounted in the drip pan and provided with a hollow elongated head, a wetting element mounted within said hollow head, means for supplying steam to the wetting element, means in said wetting element for guiding excess of moisture through the hollow wetting horn into the drip pan, a sediment pot located beneath the drip pan and connected thereto, a pump located within the hollow base and having connections with

the sediment pot, and means for controlling the operations of the pump.

2. In a machine of the class described, the combination of a hollow base, a platform secured to the top thereof, a hollow standard mounted on the top of the platform, a fluid heating element located in the top of said hollow column, a horn mounted on the platform, a wetting element located in the top open end of the horn, a conduit extending from the heating element to the steaming element, controlling means located in said conduit for regulating the supply of steam to the steaming element, moisture collecting means mounted on the platform at the base of the wetting horn, a sediment pot provided with a plurality of chambers located beneath the platform, a conduit connecting the moisture collecting means with the lower chamber of the sediment pot, a conduit connecting the upper chamber of said sediment pot with the pump in the base, and means for controlling the operations of the pump at will.

3. An improved wetting or steaming element comprising a wetting horn provided with a dish-like elongated upper end, a hollow member provided with a plurality of perforations extending upwardly from the interior thereof, the upper face of the hollow member being bevelled and provided on its periphery with a plurality of V shaped passages for guiding excess moisture from the top of the wetting element to the wetting horn, and means for supplying steam or hot water to the hollow member.

In testimony whereof, I have signed my name to this specification.

SIDNEY C. WILSON
